SANDING MACHINE

George A. Schipper, Aurora, Ind.

Application January 14, 1930. Serial No. 420,707

10 Claims. (Cl. 51—67)

My invention relates to sanding machines, and in part to certain improvements over the sanding machines disclosed in my co-pending application, Serial No. 295,247, filed July 25, 1928.

5 The principal object of the present invention is to provide a sanding machine of rotary type in which spindles, or other similar pieces, may be sanded with great speed, and in which the work may be inserted and removed from the machines 10 at times when the carrying spindles have stopped, thus facilitating and making safe the insertion, removal and centering of the work.

A further object of the invention is to provide a construction wherein the head stock spindles 15 are movable, instead of the tail stock spindles, for the removal of work therefrom.

A still further object of the invention is to provide a clutch mechanism for the movable head stock, of such a nature that the loading of the 20 work tends to reenforce and augment the work pressure thereby rigidly securing the work between the head and tail stocks.

Further objects of the invention will appear from the following detailed description thereof.

25 In the drawings:

Figure 1 is a front view of a sanding machine constructed in accordance with this invention.

Figure 2 is an end view of said machine.

Figure 3 is a section of one of the head stock 30 spindles and connections.

Figure 4 is a sectional view of a detail.

Figure 5 is an elevation, partly in section, of the sanding frame oscillating connections.

The numeral 1 indicates the main frame of my 35 new sanding machine. Mounted between standards 2 and 3 of said machine is a rotating shaft 4. Also mounted in bearings on the frame 1 is a power shaft 5 having a pulley 6 arranged to be connected to any suitable source of power.

40 The shaft 5 is also provided with a pulley 7 inside the frame which is connected by means of a belt 8 with a pulley 9 mounted on a shaft 10 in a bearing carried by bracket 11 secured in the frame. The outer end of the shaft 9 carries a

45 worm 12 engaging a worm wheel 13 securely mounted on a shaft 14 mounted in bearings on bracket 15 secured to the frame. The shaft 14 carries a bevel gear 16 rigidly secured which intermeshes with a similar gear 17 carried by an oblique shaft 18 mounted in bearings, one of 50 which is in the bracket 15, and the other in a bracket 19 secured to the frame. The upper end of the shaft 18 carries a bevel gear 20 which intermeshes with a large bevel gear 21 keyed in the 55 outer end of the main shaft 4. It will thus be

seen that the rotation of the power shaft 5 will cause the main shaft 4 to rotate at a slower rate of speed.

The tail stock spindles 22 are rotatable in bearings 23 carried by a circular tail plate 24 carried by a hub 25 which is slidable on the shaft 4, but which may be rigidly locked against longitudinal movement by means of a locking device 26. The tail stock spindles 22 have no individual longitudinal movement, but are collectively movable 60 by sliding the tail plate 24 on the shaft 4 as indicated.

The head stock spindles 27 are carried between two circular plates 28 and 29, which are carried by a hub 30 through which set screws 31 70 pass to secure the plate rigidly on the shaft 4. The head stock spindles 27 and tail stock spindles 22 are, of course, centered in pairs.

The spindles 27 are slidable in sleeves 32, see Figure 3, and are interlocked therewith by means of cam teeth 33 on the spindles which fit into correspondingly shaped notches 34 in the sleeves. The sleeves 32 are mounted in ball bearings 35 and 36 carried respectively by the plates 28 and 29, and are provided with pulleys 37 which are 80 keyed thereon. The rear end of each of the sleeves 32 is provided with a cap 38 threaded thereon, the spindle 27 extending through a central opening in said cap, and being provided on its outer end with a flanged head 39. The interior portion of the spindle 27 is of reduced dimension, and may be a separate rod securely fixed in the inner end of the spindle proper, if desired, as shown in Figure 3. A compression spring 40 is mounted inside the sleeve 32 around the 90 reduced portion of the spindle, and abuts against the shoulder formed by the spindle proper and against the cap 38.

Mounted in brackets 41 secured on the annular plate 28 are bell cranks 42, each of which is 95 provided with a yoke head 43 adapted to abut against the flange 39 of one of the spindles, the other arm of each of the bell cranks is provided with a roller 44 which is adapted to be engaged by the cam surface 46 of an arcuate plate 47 100 which is secured on the standard 2 of the frame, the plate 47 thus serving to rock the bell cranks at suitable intervals during the rotation of the shaft 4 to withdraw the head stock spindles and release the work.

Securely mounted on the shaft 5, is a pulley 48, and rotatably mounted on a shaft 49 carried by the upper end of the standard 2 is a pulley 50. Also rotatably mounted on a shaft 51 carried by a pivotally mounted arm 52 is a pulley 53. 105 110

Each of the pulleys 48, 50 and 53, as well as each of the pulleys 37 carried by the spindle sleeves 32 is provided with a plurality of grooves within which round belts 54 operate, the belts being disposed as shown in Figure 2 so as to operatively connect with such of the pulleys 37 as are toward the rear of the machine and in position to bring the work into contact with sanding brushes 55 carried between frames 56, the pivoted pulley 53 serving as an idler properly to tension the belt. The frames 56 are adjustable by means of bolts 57 operating in slots in extensions 58 of hanging frames 59 toward and away from the work carried by the spindles. Frames 59 are pivoted on links 60, the upper ends of said links being pivotally connected to brackets 61 secured on a rod 62 carried by rear standards 63 supported by the frame. The lower ends of the frames 59 are secured to a shaft 64 which is caused to reciprocate in the frame 1 by means of a rod 65 which is pivotally connected with an arm 66 rigidly secured on the shaft 64, the other end of the rod 65 is provided with a head 67 having a circular opening within which an eccentric 68 secured on the end of shaft 14 operates.

The operation of my new sanding machine is as follows:

Power being applied to the pulley 6, the shaft 4 is caused to rotate at the desired speed, also the head stock spindles 27 to the rear of the machine, are rotated by means of the belts 54 which contact with the pulleys 37 of said spindles. The operator standing at the front of the machine has dead spindles within which to feed the work and from which to remove the same. The spindles, however, continuing to revolve around the axis of shaft 4, work thus placed between the work carrying spindles is brought into contact with the sanding brushes during approximately one half of the time required for the rotation of the shaft 4, during which time the work is revolved by the carrying spindles. When each spindle in turn is thus brought into position where its operating pulley is not engaged by the belts 54, the head stock spindle 27 is withdrawn by the connected bell crank 42 riding on the cam plate 47, and the finished piece is thus automatically released from the machine. A new piece may then be inserted between the spindles, and the bell crank passing beyond the plate 47 is released permitting the compression spring 40 to force the spindle 27 against the piece to be operated on. By reason of the sloping edges of the notches 34 and teeth 33, the loading on the work tends to cause a relatively faster movement of the sleeve with respect to the spindle, thus forcing the spindle outwardly and causing it to grip more firmly the piece operated on. Excess loading, which might otherwise cause undesired removal of the work from the spindles, in my present construction is thus utilized to cause the spindles more firmly to grip the same.

It will be noted further that by reason of the placement of the tension mechanism of the spindles in the head stock, it is possible to lighten the general frame construction and permit the tail stock to be supported entirely by the rotating shaft thus simplifying and materially reducing the cost of construction.

During the operation of the machine, the sanding brushes are oscillated longitudinally over the work in a manner similar to that performed by the machine described in my said co-pending application.

Having thus fully described my invention, what

I claim as new and desire to secure by Letters Patent is:

1. In a sanding machine, a head spindle construction comprising a plate, a sleeve rotatably mounted in said plate, a spindle slidably mounted in said sleeve, means for normally forcing said spindle outwardly to hold work, a tooth on said spindle, the rear edge of said tooth comprising a cam surface diverging from its end in the direction opposite to the direction of spindle rotation, said sleeve being provided with a notch for said tooth of shape corresponding to said tooth whereby the loading on said spindle will cooperate with said outwardly forcing means. 80

2. In a sanding machine, a head spindle construction comprising a plate, a sleeve rotatably mounted in said plate, a spindle slidably mounted in said sleeve, a spring mounted in said sleeve and arranged to force said spindle outwardly to hold work, a tooth on said spindle, the rear edge of said tooth comprising a cam surface diverging from its end in the direction opposite to the direction of spindle rotation, said sleeve being provided with a notch for said tooth of shape corresponding to said tooth, whereby the loading on said spindle will cooperate with said spring. 90

3. In a sanding machine, a head spindle construction comprising a pair of plates, a sleeve rotatably mounted in said plates, a spindle slidably mounted in said sleeve, means for normally forcing said spindle outwardly to hold work, a tooth on said spindle, the rear edge of said tooth comprising a cam surface diverging from its end in the direction opposite to the direction of spindle rotation, said sleeve being provided with a notch of shape corresponding to said tooth, whereby the loading on said spindle will cooperate with said outwardly forcing means. 105

4. In a sanding machine, a head spindle construction comprising a pair of plates, a sleeve rotatably mounted in said plates, a spindle slidably mounted in said sleeve, a spring mounted in said sleeve and arranged to force said spindle outwardly to hold work, a tooth on said spindle, the rear edge of said tooth comprising a cam surface diverging from its end in the direction opposite to the direction of spindle rotation, said sleeve being provided with a notch of shape corresponding to said tooth, whereby the loading on said spindle will cooperate with said spring. 115

5. In a sanding machine, a rotating shaft, a pair of plates rigidly mounted on said shaft, a plurality of sleeves rotatably mounted in said plates and disposed radially around said shaft, pulleys carried by said sleeves, a belt, pulleys for operating a belt on one side of said shaft to operatively engage said first mentioned pulleys during a fractional part of their rotation around the axis of said shaft to actuate said sleeves, 130 a spindle slidably mounted in each of said sleeves, a tooth on each of said spindles, the rear edges of said teeth being cam surfaces diverging from the teeth ends in the direction opposite to the direction of spindle rotation, each of said sleeves being provided with a notch for its spindle tooth of shape corresponding to said tooth, whereby said sleeve and spindle are interlocked and the loading on said spindle is arranged to force the same toward said load. 135

6. In a sanding machine, a rotating shaft, a pair of plates, rigidly mounted in said shaft, a plurality of sleeves rotatably mounted in said plates and disposed radially around said shaft, pulleys carried by said sleeves, a belt, pulleys for 140

- operating a belt on one side of said shaft to operatively engage said first mentioned pulleys during a fractional part of their rotation around the axis of said shaft to actuate said sleeves, springs 5 mounted in said sleeves arranged to force the spindles outwardly to hold work, a tooth on each of said spindles, the rear edges of said teeth being cam surfaces diverging from the teeth ends in the direction opposite to the direction of spindle rotation, each of said sleeves being provided with a notch for its spindle tooth of shape corresponding to said tooth, whereby said sleeve and spindle are interlocked and the loading on said spindle will cooperate with said spring. 10
- 15 7. In a sanding machine, a rotating shaft, a plate slidably mounted on said shaft, a plurality of tail spindles rotatably mounted in said plate and disposed radially around said shaft, a pair of plates rigidly mounted on said shaft, a plurality 20 of sleeves rotatably mounted in said plates and disposed radially around said shaft, and severally in axial alignment with said tail spindles, pulleys carried by said sleeves, a belt, pulleys for operating a belt on one side of said shaft to operatively engage said first mentioned pulleys during a fractional part of their rotation around the axis of said shaft to actuate said sleeves, a spindle 25 slidably mounted in each of said sleeves, means for normally forcing said spindles toward said tail spindles, a tooth on each of said spindles, the rear edges of said teeth being cam surfaces diverging from the tooth ends in the direction opposite to the direction of spindle rotation, each of said sleeves being provided with a notch for the spindle tooth of shape corresponding to said tooth, whereby said sleeve and spindle are interlocked 30 and the loading on said spindle is arranged to force the same toward its tail spindle, a plurality of bell cranks pivotally mounted on the outer of said pair of plates, one end of each of said bell cranks being arranged to engage one of said 35 tail spindles, a cam plate fixedly mounted in the path of travel of the other ends of said bell cranks during the rotation of said shaft, whereby said bell cranks are caused periodically to withdraw said spindles. 105
- 35 8. In a sanding machine, a rotating shaft, a plate slidably mounted on said shaft, a plurality of tail spindles rotatably mounted in said plate and disposed radially around said shaft, a pair of plates rigidly mounted on said shaft, a plurality 40 of sleeves rotatably mounted in said plates and disposed radially around said shaft, and severally in axial alignment with said tail spindles, pulleys carried by said sleeves, a belt, pulleys for operating a belt on one side of said shaft to operatively engage said first mentioned pulleys during a fractional part of their rotation around the axis of said shaft to actuate said sleeves, a spindle 45 slidably mounted in each of said sleeves, springs mounted in said sleeves and arranged to force said spindles toward said tail spindles, a tooth on each of said spindles, the rear edges of said teeth being cam surfaces diverging from the tooth ends in the direction opposite to the direction of spindle rotation, each of said sleeves being provided with a notch for its spindle tooth of shape 50 corresponding to said tooth, whereby said sleeve and spindle are interlocked and the loading on said spindle is arranged to force the same toward its tail spindle. 115
- 55 9. In a sanding machine, a rotating shaft, a plate slidably mounted on said shaft, a plurality of tail spindles rotatably mounted in said plate and disposed radially around said shaft, a pair of plates rigidly mounted on said shaft, a plurality 60 of sleeves rotatably mounted in said plates and disposed radially around said shaft, and severally in axial alignment with said tail spindles, pulleys carried by said sleeves, a belt, pulleys for operating a belt on one side of said shaft to operatively engage said first mentioned pulleys during a fractional part of their rotation around the axis of said shaft to actuate said sleeves, a spindle slidably mounted in each of said sleeves, springs mounted in said sleeves and arranged to force said spindles toward said tail spindles, a tooth on each of said spindles, the rear edges of said teeth being cam surfaces diverging from the tooth ends in the direction opposite to the direction of spindle rotation, each of said sleeves being provided with a notch for its spindle tooth of shape corresponding to said tooth, whereby said sleeve and spindle are interlocked and the loading on said spindle is arranged to force the same toward its tail spindle. 125
- 65 10. In a sanding machine, a rotating shaft, a plate slidably mounted on said shaft, a plurality of tail spindles rotatably mounted in said plate and disposed radially around said shaft, a pair of plates rigidly mounted on said shaft, a plurality of sleeves rotatably mounted in said plates and disposed radially around said shaft, and severally in axial alignment with said tail spindles, pulleys carried by said sleeves, a belt, pulleys for operating a belt on one side of said shaft to operatively engage said first mentioned pulleys during a fractional part of their rotation around the axis of said shaft to actuate said sleeves, a spindle 70 slidably mounted in each of said sleeves, springs mounted in said sleeves and arranged to force said spindles toward said tail spindles, a tooth on each of said spindles, the rear edges of said teeth being cam surfaces diverging from the tooth ends in the direction opposite to the direction of spindle rotation, each of said sleeves being provided with a notch for its spindle tooth of shape corresponding to said tooth, whereby said sleeve and spindle are interlocked and the loading on said spindle is arranged to force the same toward its tail spindle, a plurality of bell cranks pivotally mounted on the outer of said pair of plates, one end of each of said bell cranks being arranged to engage one of said tail spindles, a cam plate fixedly mounted in the path of travel of the other ends of said bell cranks during the rotation of said shaft, whereby said bell cranks are caused periodically to withdraw said spindles. 130
- 75 11. In a sanding machine, a rotating shaft, a plate slidably mounted on said shaft, a plurality of tail spindles rotatably mounted in said plate and disposed radially around said shaft, a pair of plates rigidly mounted on said shaft, a plurality of sleeves rotatably mounted in said plates and disposed radially around said shaft, and severally in axial alignment with said tail spindles, pulleys carried by said sleeves, a belt, pulleys for operating a belt on one side of said shaft to operatively engage said first mentioned pulleys during a fractional part of their rotation around the axis of said shaft to actuate said sleeves, a spindle slidably mounted in each of said sleeves, springs mounted in said sleeves and arranged to force said spindles toward said tail spindles, a tooth on each of said spindles, the rear edges of said teeth being cam surfaces diverging from the tooth ends in the direction opposite to the direction of spindle rotation, each of said sleeves being provided with a notch for its spindle tooth of shape corresponding to said tooth, whereby said sleeve and spindle are interlocked and the loading on said spindle is arranged to force the same toward its tail spindle. 135
